UNITED STATES PATENT OFFICE

2,633,692

WIRE ROPE-MAKING MACHINE

William T. MacCreadie, Lewisburg, Pa.

Application November 17, 1948, Serial No. 60,487

3 Claims. (Cl. 57—62)

1

This invention is a wire rope-making machine and may be particularly termed a high speed strander.

This invention combines a tube or drum strander and a twister arranged in such manner that a multiple lay is made with each turn of the machine, provision being made for a proper turn back.

A particular object of the invention is to provide a strander using, in combination, a tube strander and a twister, so associated with one another as to produce multiple twists in the strand, thereby increasing production without increasing the speed of the machine.

A further object of the invention is to provide novel means for associating a tube or drum strander with a twister so as to bring about the desired results.

A further object of the invention is to provide means whereby a tube, drum or other strander may be combined with a twister in such manner that one of these machines will be operated in a direction the reverse of the other.

With the foregoing objects in view, together with others which will appear as the description proceeds, the invention consists in the novel combination and arrangement of parts, all as will be described more fully hereinafter, illustrated in the drawing, and particularly pointed out in the claims.

In the drawings:

Fig. 1 is a plan view of a tube or drum stranding machine.

Fig. 2 is a similar view of a twister machine.

Fig. 3 is a side elevation of the machine shown in Fig. 1.

Fig. 4 is a similar view of the machine shown in Fig. 2.

Fig. 5 is a sectional view taken substantially upon line 5—5 of Fig. 1.

Fig. 6 is an enlarged fragmentary longitudinal section taken through a part of the machine shown in Fig. 1.

Fig. 7 is a fragmentary sectional view through one end of the haul-off device.

Figure 8 is a fragmentary longitudinal sectional view of one end of the wind-up section of the machine.

Fig. 9 is a similar view of the opposite end of the wind-up section.

Fig. 10 is a side elevation of a Reeves transmission mechanism showing its association with the present machine.

Fig. 11 is a sectional view taken substantially upon line 11—11 of Fig. 2.

2

Fig. 12 is a fragmentary elevation showing a conventional reversing mechanism.

Fig. 13 is a perspective view of a modified form of bobbin carriage.

Fig. 14 is a fragmentary side elevation of the tube or drum strander and illustrating as applied thereto the modified form of bobbin carriage as shown in Fig. 13, and

Fig. 15 is a fragmentary view of a part of the haul-off frame and showing a slight modification.

The machine consists essentially in a strander, preferably of the tube or drum type, associated with a wind-up commonly used in a twister, the latter operating in a direction opposite to that of the strander. The strand produced by the tube or drum strander passes in its finished form from the same to a twister operating in the reverse direction, which twister includes a wind-up bobbin to receive the finished strand.

Referring now more particularly to the drawings, and particularly to Figs. 1 and 3 thereof, 15 represents an elongated barrel or tube of hollow construction supported for rotation upon rollers 16 mounted in brackets 17 carried by the bed 18 of the machine. This drum is provided at one end (Fig. 6) with an axially disposed stub shaft 19 rotatably mounted in a bearing 20, the outer end of the said stub shaft having rigidly secured thereto a sprocket wheel 21. This sprocket wheel has a chain 22 passing thereover and also around sprocket 23 affixed to the shaft 24 of a motor 25 constituting the source of power for the machine.

Arranged within the drum and adjacent to the power receiving end thereof is a bobbin carriage 26 having trunnions 27 and 28 at its ends rotatably mounted axially of the drum in webs 29 constituting a part of the drum or tube 15. The trunnion 27 has affixed thereto a gear 30 in mesh with the teeth of a gear 31 carried by shaft 32 rotatably supported within the drum 15, which shaft also has affixed thereto a gear 33 whose teeth are in mesh with the teeth of gear 34 affixed to or forming a part of the stationary bearing 20. It is apparent from this construction that rotation of sprocket 21 by the power source will cause the drum 15 to rotate, while at the same time rotary movement is also imparted to the bobbin carriage 26 by means of the gears 30, 31, shaft 32 and gears 33—34. By varying the sizes of the gears mentioned, a desired speed ratio between the cylinder or drum and the bobbin carriage may be obtained.

The trunnion 28 at the opposite end of the bobbin carriage extends through and has bearing

in the adjacent web 29, and has affixed thereto a gear 35 in mesh with a gear 36 carried by shaft 37 rotatably mounted in the webs 29. The shaft 37 also has affixed thereto a gear 38 in mesh with gear 39 forming a part of trunnion 27 of the next adjacent bobbin carriage 26. Bobbin carriages in any desired number may be arranged throughout the length of the cylinder or drum and intergeared in the manner described so as to rotate in unison. Three of the bobbin carriages are shown in the present instance, but it will be understood that any desired number may be employed, depending upon the number of wires required in the completed strand.

Each of the bobbin carriages is provided with a transversely disposed bobbin shaft 40 upon which is rotatably mounted a bobbin 41 containing a wire 42. It may be desirable to provide braking means for the bobbins, in which event a brake shoe 43 affixed to a slideable spindle 44 may be used, as shown in detail in Fig. 6. This spindle is slidably seated in an axial bore 46 in the trunnion 27, and carries a nut 45 to govern the tension of a spring 48 for obvious purposes. The brake mechanism described is conventional, and it is understood that any other desired braking or speed controlling means may be used in connection with the several bobbins.

The trunnion 28 of each bobbin carriage is provided with an axial bore or opening 49 through which passes the wire 42 from the adjacent bobbin. After passing through the bores 49 the wires lead outwardly therefrom and through suitable openings in the webs 29 and forwardly of the cylinder to the head at the opposite end thereof, through which they pass and converge as shown in Figs. 1-3 in a twister die 50 disposed in axial alignment with the cylinder or drum and mounted in the supporting posts 51.

Due to the fact that the cylinder or drum rotates, this die might be held stationary and the twisted wires pulled through in the well known manner. However, in the present instance, this die is rotatably mounted in the supporting posts 51 and is turned in a direction opposite to the direction of rotation of the cylinder, whereupon an additional twist is accomplished. The die, therefore, is affixed to shaft 52 rotatably mounted in the support posts 51, and a sprocket 53 is affixed to said shaft. A sprocket chain 54 passes over the sprocket 53 as well as over a sprocket 55 affixed to a countershaft 56 mounted in suitable bearings 57 at one side of the machine. The countershaft 56 also carries a sprocket 58 over which passes a chain 59 engaged with a sprocket 60 secured to a jack shaft 61 mounted in bearings 62 beside the machine. The jack shaft 61 has affixed thereto a gear 63 in mesh with a gear 64 secured to a shaft 65 mounted in bearing 66 at the side of the machine. The shaft 65 at its far end has affixed thereto a sprocket 67 having a chain 68 passing thereover and also over a sprocket wheel 69 affixed to the drive shaft 24 of the motor 25.

From this construction it is apparent that the motor 25 through the sprocket and chain connections 21-22-23 causes the drum or cylinder 15 to rotate upon its supporting rollers 16 in one direction while at the same time through the sprocket and chain connection 61, 68, 69 the shaft 65 is caused to rotate the twister die 50 in a direction opposite to the rotative direction of the cylinder by means of the gears and sprocket and chain connections just described.

The shaft 52 which carries the twister die 50 has a central longitudinal opening therein as will

be understood, through which the twisted strand 70 passes. This strand also passes through a longitudinal opening in a trunnion 71 aligned with the twister die shaft and supported in the bearing post 72 which supports the haul-off carriage 73. This carriage has a hollow trunnion 74 at its opposite end (see Fig. 7) through which extends a longitudinally apertured shaft 75 having affixed to its inner end a spur gear 76 engaged with a gear 77 secured to a shaft 78 mounted in a suitable bearing within the haul-off carriage and disposed longitudinally thereof. The shaft 78 has a bevel pinion 79 affixed thereto in mesh with a bevel gear 80 affixed to the transverse shaft 81 mounted for rotation centrally within the haul-off carriage and supporting the haul-off drum 82. The hollow trunnion 74 is rotatably supported in the bearing post 72, and has integrally or rigidly secured thereto a sprocket 83 over which passes a power chain 84 engaged with the teeth of a sprocket wheel 85 affixed to the shaft 56. The latter shaft is rotatably mounted in suitable bearings 86 at the side of the machine.

The shaft 75 with its spur gear 76 remains stationary, and to this end is affixed at one end to a bracket 87 affixed by a pin 88 to the bearing post 72. (See Fig. 4.)

The tube machine shown in Fig. 1 produces a completed strand ready for use as a complete cable. However, by combining the mechanism shown in Fig. 2 with the tube machine of Fig. 1, greater cable or rope making speed is obtained. The die 50 rotates in a direction opposite to the direction of twisting movement of the converging wires 42 from the tube machine, and the completed strand 70 is given a twist by the haul-off drum 82 in the same direction of rotation as the die 50 just prior to its entry to said die. It is therefore apparent that by combining the two machines in the manner described and as illustrated, a greater quantity or length of completed cable or strand is produced than has been heretofore possible with a machine of the type shown in Fig. 1.

The wind-up bobbin for the completed strand or cable is indicated at 89, and rotates while being held stationary against lateral rotary movement. This bobbin is keyed to the wind-up bobbin shaft 90 rotatably mounted in the carriage 91 carried by the rotatable frame work or flyer 92. The carriage 91 is provided at one end (see Fig. 8) with a hollow trunnion 93 through which extends and is rotatably mounted a stub shaft 94 having affixed to its outer end a gear 95 and to its inner end a spur gear 96 in mesh with a similar gear 97 rotatably engaged in the end wall of carriage 91 and having a sprocket wheel 98 affixed to its outer end. A chain 99 passes over the sprocket wheel 98 as well as over a sprocket wheel 100 affixed to a countershaft 101 rotatably mounted at the side and longitudinally of the carriage 91. The inner end of shaft 101 has affixed thereto a bevel pinion 102 in mesh with a similar gear 103 affixed to the wind-up bobbin shaft 90. A bevel pinion 104 is secured to the inner end of a shaft 105 mounted for rotation in suitable bearings 106 affixed to the carriage 91, and the outer end of shaft 105 has affixed thereto a bevel pinion 107 in mesh with a similar gear 108 secured to a reversing screw shaft 109 rotatably mounted transversely of and in the carriage 91. This reversing screw shaft (see Figs. 11 and 12) is engaged by a traveller 110 slidably mounted upon the traveller shaft 111, and is equipped with guide pins 112 between which the cable 70 passes.

The inner end of the frame work 92 is provided

with a hollow trunnion 113 (see Fig. 8) which is rotatably mounted in the supporting post 114. This trunnion has rotatably mounted therein a sprocket gear 115 attached to or integral with a gear 116. The gear 116 is in mesh with a similar gear 117 secured to a shaft 118 mounted for rotation in the frame work 92, which shaft also carries a gear 119 in mesh with gear 95.

The outer end of the wind-up bobbin carriage 91 is provided with a hollow trunnion 122 (see Fig. 9) which is rotatably mounted in a part of the frame work 92. This trunnion is in axial alignment with the frame work, and has affixed to the outer end thereof a gear 123 in mesh with a similar gear 124 affixed to a shaft 125 rotatably mounted in the frame work 92 and disposed longitudinally thereof. The shaft 125 projects beyond the frame work 92 and has affixed thereto a gear 126 in mesh with a gear 127 rigidly secured to or integral with the supporting post or bearing member 128. This end of the frame work 92 is provided with a trunnion 129 rotatably mounted in the bearing post 128 and having a belt pulley 130 affixed thereto. A belt 131 passes over this pulley and also over a similar pulley 132 affixed to shaft 56 for the purpose of rotating the frame 92.

It is desirable that means be employed between the haul-off mechanism and the wind-up mechanism to maintain the proper tension in the completed cable as it is led to the wind-up bobbin. Any desired brake or control mechanism may be employed, either friction or otherwise, but in the present instance I have illustrated a conventional Reeves transmission between the haul-off drum and the bobbin wind-up mechanism for this purpose.

Interposed between the haul-off drum 82 and the wind-up bobbin 89 is the Reeves transmission represented generally at RT. This transmission includes a pair of coating cone pulleys 133-134 keyed as at 135 for longitudinal sliding movement upon shaft 56. The transmission also includes a jack shaft 136 spaced from and parallel to shaft 56 similarly equipped with coating cone pulleys 137-138 keyed for sliding movement upon said jack shaft as at 139. A belt 140 passes over the pulleys 133-134 and 137-138. The shaft 136 is provided at one end with a sprocket 141, over which passes a chain 142 engaged with the sprocket wheel 115 affixed to the gear 116. It is apparent, therefore, that rotary movement of shaft 56 will operate belt 140 to jack shaft 136 which, in turn, through sprockets 141-115 and chain 142 will cause the shaft 118 to rotate and to transmit power to bobbin 89.

The cable 70 as it leaves the haul-off drum 82 passes through the hollow shaft 75 and through the hollow trunnion 113 to the interior of the frame work 92. A guide pulley 143 secured to the frame work 92 leads the cable 70 laterally of the frame work 92 and over a guide pulley 144 from whence the cable passes outwardly and longitudinally of the frame work 92 to a guide pulley 145, then inwardly toward the center of the drum and over guide pulley 146 and through a hollow trunnion 147 rotatably mounted in the frame 92 and forming the outer support for the carriage 91. The cable then passes between the guides 112 of the traveller and onto the wind-up bobbin 89.

The Reeves transmission includes means for governing the speed of the machine in accordance with the tension of the cable leading from the haul-off drum to the wind-up bobbin. As shown particularly in Figs. 2, 4 and 10, the

sliding movements of the cone pulleys 133-134 and 137-138 are governed by rocking movements of the bars 150 and 151. These bars, arranged in spaced parallel relationship, are pivoted intermediate their ends as at 152 within the frame of the transmission, and their ends engage the rear faces of the cone pulleys. Rocking movement of these bars, therefore, will permit the cooperating cone pulleys at one end of the casing or frame to move apart, while the cooperating cone pulleys at the opposite end of the frame are moved toward one another. A toggle lever 153 is connected to an upstanding oscillatory shaft 154 pivoted in the frame of the transmission, and the upper end of this shaft has attached thereto an arm 155, to the opposite ends of which links 156 and 157 connect the said arm with the members 150 and 151 respectively.

20 A weight 158 has an eye 159 through which the cable loosely passes, and this weight has pivotally connected thereto one arm of a bell crank lever 160, the opposite arm 161 of which is connected with a rock lever 162 pivoted as at 163 to the bearing post 114, the lower end of the rock lever 162 being connected by a link 164 with the inner end of the toggle lever 153.

25 From the foregoing it is apparent that when power is applied to the machine from the motor 25, the drum or cylinder 15 will rotate and the wires 42 will unwind from their spools or bobbins to be led forwardly from the cylinder into converging relationship into the twister die 50, which die, due to the fact that it is moving in a direction reverse from the direction of movement 30 of the cylinder, gives an additional twist or lay to the cable because of twisting action applied to the cable by the flyer 92 and the haul-off 35 73. As the cable is pulled through the twister die by the haul-off drum 82 it passes to the wind-up bobbin, and the tension will at all times be automatically maintained by the Reeves transmission, or some other tensioning device. From the tensioning device the cable passes outwardly within the frame work 92 and is then led backwardly and centrally thereof through the lapping or guide device and properly wound upon the rotating wind-up bobbin. It is apparent that the drum or cylinder machine brings about a first twisting of the wires into 40 a completed cable, whereupon the die rotating in a reverse direction imposes upon the cable an additional twist before it passes through the die. Since these combined machines rotate in opposite directions, two twists are produced for 45 every turn of the machines.

50 In Figs. 13 and 14 of the drawing, there is illustrated a modified form of bobbin and carriage which may be substituted for the bobbins 41 in the cylinder or drum 15. In this modification, the bobbin 41a is rotatably supported in a drop center carriage 170 pivoted at 170' in the bobbin carriage 26 so that the center of gravity of the carriage is below the median line 55 of the cylinder. Because of this construction, the carriage remains at all times in an upright position. The wire 42 passes from the bobbin rearwardly and over guide pulleys 171, 172, 173 and 174, from whence they pass through a hollow trunnion 175 to a guide pulley 176, thence to a similar pulley 177 near the outer periphery of the cylinder or drum. The wire then leads forwardly of the cylinder or drum and to the twisting die in the manner heretofore described.

70 In Fig. 15 of the drawings there is shown a

further modification. In the preferred form of the invention, the twister die 50 is shown as being specially driven from the shaft 56. A special drive for the twister die, however, may be dispensed with. In Fig. 15 the haul-off frame 73 is shown as having the twister die 50 affixed to the hollow supporting trunnion 71. It is obvious, therefore, that as rotation of the haul-off frame or cradle 73 is in a direction opposite to the direction of rotation of the cylinder 15, the twister die will give the additional twist after a special drive connection.

I claim:

1. In a rope making machine, means for twisting a plurality of wires into a cable, a die 15 to receive said cable, means for rotating said die in a direction opposite to the direction of cabling twist of said wires, means beyond said die for giving a twist to said cable as it enters said die, and a wind-up bobbin to receive the 20 cable from said die.

2. In a rope making machine, means for twisting a plurality of strands into a cable, a die to receive said cable, means for rotating said die in a direction opposite to the direction of 25 cabling twist of said strands and to simultaneously twist said cable in the direction of rotation of said die as it enters the latter, and means to draw said cable through said die.

3. In a rope making machine, means for twisting a plurality of strands into a cable, a die to receive said cable, means for rotating said die in a direction opposite to the direction of cabling twist of said strands, a haul-off to draw 30 said cable through said die and to simultaneously twist said cable in the direction of rotation of

5 said die as it enters the latter, a wind-up bobbin to receive said cable, and means for controlling the tension of said cable.

WILLIAM T. MACCREADIE.
